UNITED STATES PATENT OFFICE.

PAUL S. HENDERSON, OF DENVER, COLORADO.

DESIGN FOR A DISPLAY RACK.

Application filed April 18, 1922. Serial No. 1,827. Term of patent 3½ years.

To all whom it may concern:

Be it known that I, PAUL S. HENDERSON, a citizen of the United States, and resident of the city and county of Denver, State of Colorado, have invented a new, original, and ornamental Design for Display Rack; and I do declare the following to be a full, clear, and exact description of the invention, such as will enable others skilled in the art to which it appertains to make and use the same, reference being had to the accompanying drawings, which form a part of this specification.

Fig. 1 is an end elevation of a display rack showing my new design;

Fig. 2 is a side elevation thereof; and

Fig. 3 is a perspective view thereof taken at an angle of 45° to the showings of the other figures.

I claim:

The ornamental design for a display rack as shown.

In testimony whereof I affix my signature.

PAUL S. HENDERSON
